(57) **CLAIM**

The ornamental design for a protective case for earphone, as shown and described.

DESCRIPTION

FIG. 1 is a front, right and bottom perspective view of a protective case for earphone, showing my new design; FIG. 2 is a rear, left and top perspective view thereof; FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof;

FIG. 9 is an enlarged view of area "9" in FIG. 1; and, FIG. 10 is an enlarged view of area "10" in FIG. 2.

The even broken lines shown in the drawings illustrate portions of the protective case for earphone. The long-short dashed broken lines indicate bounds of the enlarged views. None of the broken lines form part of the claimed design.
